(57) **CLAIM**

The ornamental design for a liner for aircraft waste system as shown and described.

DESCRIPTION

FIG. 1 is a top perspective view of a liner for aircraft waste system showing my new design.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines shown in the Figures show portions of the liner for aircraft waste system that form no part of the claimed design.

The shade lines in the Figures show contour and do not claim surface ornamentation or treatment.
